WINDOW REGULATOR

John H. Roethel, Detroit, Mich., assignor to
 Roethel Engineering Corporation, Detroit,
 Mich., a corporation of Michigan

Application January 29, 1943, Serial No. 473,915

17 Claims. (Cl. 268—126)

1

This invention relates to window regulators for raising and lowering glass or transparent panels or the like of vehicles, particularly automobile bodies, an object of the invention being to provide an improved window regulator which is compact, positive and efficient in operation, relatively simple in construction and economical to manufacture, capable of being easily assembled in the body, and adapted to provide not only a desirable handle location but also to maintain the window panel substantially level during its travel between raised and lowered positions.

A further object of the invention is to provide a new window regulator of the two arm type which will support the window panel at spaced points, in which the two arms are positively controlled in improved manner and mounted compactly upon a single support or mounting plate whereby installation is facilitated and the window panel held substantially level against any material tilting in its plane during operation.

Heretofore so-called double arm or two arm window regulators used extensively in automobile bodies of certain makes have been of three principal types, i. e. the so-called parallel arm regulator such as shown in U. S. Patent No. 2,103,223, the so-called double arm compound gear window regulator such as shown in U. S. Reissue Patent No. 19,579, and the cross arm window regulator such as shown in U. S. Patent No. 2,168,242. These regulators have many advantages and desirable features. However, the parallel arm regulator, while inherently providing a desirable remote handle location, has the disadvantage of two arms swinging equal distances in the same direction thereby tending to shift the glass laterally. The compound gear regulator, while avoiding this disadvantage by reason of having two diverging arms which swing equally in opposite directions, fails inherently to provide a desirable remote handle location without the interposition of gearing. Also, in this regulator the points of connection of the arms to the glass have undesirably too wide a spread in the half-way position. The cross arm regulator has the disadvantage of requiring two separate supports for the arms, one arm being pivoted to a mounting plate and the other slidingly connected at a distance therefrom to the inner door or body panel. This renders installation more difficult and more expensive as compared with the two previous mentioned regulators which require a single mounting plate for both arms.

An important object of the present invention is to provide a window regulator of the two arm

2

type which will eliminate all of the foregoing disadvantages mentioned in respect to window regulators of the parallel arm type, double arm compound gear type and cross arm type while at the same time retaining substantially all important advantages thereof.

A further object of the invention is to provide an improved window regulator having two lift arms adapted to extend in diverging relation when the window panel is in raised position, one arm being shorter than the other and pivoted to the longer arm intermediate the ends of the latter, the shorter arm having an elbow extension and connected by a link to the mounting plate, the link being shifted by the movement of the inner end of the longer arm in such manner as to impart a pivotal motion to the shorter arm of a sufficiently compensatory nature as to cause the points of connection of the two arms with the window panel to travel up and down in substantially a common horizontal plane during operation.

Another important object of this invention is to provide a window regulator having a main swinging arm extending from a suitable fixed support or mounting plate and adapted to be connected at its outer end to the lower edge of a window panel for raising and lowering the same, the regulator also comprising a second but shorter balance arm pivoted to the main arm and adapted to be connected at its outer end to the window panel, the balance arm being positively controlled from the mounting plate so as to swing oppositely to and past the main arm during operation and at such compensated speed as to cause its point of connection with the window panel to travel the same vertical distance or to have the same range of travel as the point of connection of the main arm with the panel although traversing a shorter path.

Still a further object of this invention is to provide an improved window regulator including a pair of diverging swinging arms adapted to be connected at their outer ends to the lower edge of a window panel for raising and lowering the same, one of the arms being shorter than the other and pivoted thereto intermediate the ends of the latter, the regulator including driving means for swinging the longer arm and a positive connection between the shorter arm and the regulator mounting plate or support for swinging the shorter arm oppositely to and past the longer arm during operation of the regulator, the construction being such that, although the arms have different speeds of travel, the

points of connection of the arms with the window panel have substantially the same range of travel thereby maintaining the window panel level at all times without any material tendency to tilt or cock during operation.

Another object of this invention is to provide a window regulator having a main swinging arm extending from a suitable fixed support or mounting plate and a second lifting arm pivoted to the main arm and adapted to be connected at its outer end to the window panel, the said lifting arm being positively controlled from the mounting plate or support so as to swing oppositely to and past the main arm during operation thereby to raise and lower the window panel, the improved construction being such that the lifting arm may be employed alone to provide a single arm regulator or the main arm may be extended for connection to the window panel to provide with the other arm a two arm regulator.

Other objects of this invention will appear in the following description and appended claims, reference being had to the accompanying drawings forming a part of this specification wherein like reference characters designate corresponding parts in the several views.

Fig. 1 is a fragmentary inner side elevation of an automobile door, such as a front door having installed therein a window regulator embodying the present invention.

Fig. 2 is an enlarged side elevation illustrating the window regulator in fully raised position and also in an intermediate substantially halfway position.

Fig. 3 is a horizontal section taken substantially through lines 3—3 of Fig. 2 looking in the direction of the arrows.

Fig. 4 is a view similar to Fig. 3 illustrating the connection at the outer end of the shorter arm in uncoupled condition.

Fig. 5 is a plan view of the construction shown in Fig. 3.

Fig. 6 is a side elevation illustrating the window regulator in its lowered position.

Fig. 7 is an enlarged section taken substantially through lines 7—7 of Fig. 1 looking in the direction of the arrows.

Fig. 8 is an enlarged section taken substantially through lines 8—8 of Fig. 2 looking in the direction of the arrows.

Fig. 9 is a fragmentary view of certain operating parts of the window regulator.

Fig. 10 is a side elevation illustrating another embodiment.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

Referring to the drawings, wherein I have illustrated, by way of example, certain embodiments of the present invention constructed and adapted for the purpose of raising and lowering a window panel of an automobile body, there is shown at D a front door of an automobile body comprising a door frame 10 of any suitable construction formed with a main window opening. In the present instance this window opening is closed by means of a vertically slidable glass or other transparent panel 11 and a wing type panel 12 pivoted in con-

ventional manner about an up and down axis intermediate its front and rear edges to swing laterally. It will be understood that the present regulator may be utilized for the purpose of raising and lowering any of the windows of an automobile body and in addition may be used generally in connection with various window structures for the purpose of raising and lowering the window panels thereof.

10. The sliding panel 11 is adapted to be guided in any suitable manner within the window well, such as by means of front and rear vertically extending guides or glass run channels 13. In the present instance, the glass panels 11 and 12 are separated by means of a vertical partition bar 11a which may either be fixed within the window opening to provide a guide for the forward edge of the panel 11, or may be secured to this panel and adapted to travel therewith into the window well. Secured to the bottom edge of the panel 11 is a channel or glass retainer member 15 to which the window regulator is adapted to be connected. In the present instance, by way of example, the panel 11 is guided into and out of the window well by means of roller guide devices 14 carried by the channel 15 and adapted to travel along the guides 13.

20. In the present instance, the window regulator comprises a suitable support or mounting plate 16 which may be stamped or pressed from a sheet metal blank and having suitable screw bosses 17 by which the mounting plate may be secured within the window well to the inner door or body panel. A driving gear 18 is rotatively mounted upon the plate 16, this gear being in the form of a sector having gear teeth in meshing relation with a driving pinion mounted upon a handle shaft 19, this shaft being operated by a crank handle at the inner side of the door or body and embodying in its length a suitable friction clutch of any conventional type. In the present instance the sector gear 18 is formed integrally with a projecting lifting arm 22, herein called the main or driving arm, and this arm and gear member is secured to a pivot stud 20 journaled within the mounting plate 16. The driving arm 22 is adapted to be swung upwards and downwards about the axis of the pivot 20 upon turning the gear 18 from the pinion on the handle shaft 19. 30. The main or driving arm 22 is connected at its outer end through a stud 23 with a hanger member or bracket 24 which, as hereinafter described, is adapted to be slidably connected to the retainer channel 15 at the lower edge of the window panel. 35. Acting upon the driving arm 22, as well as the gear 18, is a spirally wound counterbalancing spring 25, the inner end of which is fastened in a slot or kerf in the end of the stud 20 and the outer end of which is connected to a lug 26 struck out from the mounting plate.

40. The regulator also comprises a second swinging arm 27, which may conveniently be termed a balance arm, and which is in the form of an elbow or angle arm having a longer arm portion 27a and a shorter angularly related arm portion 27b. The arm 27 is shorter than the main arm 22 and extends in crossed relation thereto. The arm 27 at the juncture of the arm portions 27a and 27b thereof is pivoted in overlapping relation at 28 to the main or driving arm 22, so that the angle portion 27b of the shorter arm forms a depending angular extension of the arm portion 27a. The outer end of the arm 27 is journaled upon a stud 23' and thereby connected to a second hanger member or bracket 24 slidably connected to

the retainer member 15 as hereinafter described. In the present instance the hanger members or brackets 24, as well as the stud connections 23 and 23' of the regulator arms, are identical.

It will be seen that the crank portion 27b of the arm 27 is in the form of a substantially right angular depending extension which extends below the driving arm 22. In the present instance the pivotal connection 28 between the balance arm 27 and the main arm 22 is at a point offset from the longitudinal center of the driving arm. In this embodiment the arm 22 is provided with a lateral extension 22a and the pivot 28 is located in this extension, as illustrated in the drawings, at a predetermined distance from the point X located at the intersection of two perpendicularly disposed lines extending centrally through the arms 22 and 27. Pivoted at 31 to the lower end of the extension 27b is a control link or bar 32. This link or bar extends generally in the direction of the arm 22 and at its inner end it is pivoted at 33 to the outer end of the lever 34. The opposite or inner end of this lever is pivoted by means of a stud 35 to a lateral extension 36 of the arm and gear member 18, 22. The lever 34, intermediate the pivots 33 and 35, is fulcrumed upon the mounting plate 16 through the medium of a shoulder rivet 37, see particularly Fig. 8. The rivet is secured rigidly to the lever 34 and is journaled within a flanged vertical slot 38 in the mounting plate, see Figs. 2 and 8. Thus it will be seen that the lever 34 positively connects the driving arm and gear member 18, 22 to the control link 32, power being applied to the lever at the point 35 above the fulcrum 37 and being transmitted to the control link at the point 33 at the opposite side of the fulcrum. Hence, it will be seen that upon rotation of the gear 18 the lever 34 will be swung about its fulcrum 37 thereby shifting the control link 32 endwise and imparting predetermined pivotal motion to the lifting arm 27.

A quick detachable connection is provided at 23 and 23' between the outer ends of the lifting arms 22 and 27 and the lower edge of the window panel. An advantageous construction by which this is accomplished is illustrated in Figs. 2 to 5 inclusive and is identical for each arm. Each stud 23 or 23' has a slotted head to receive a screw driver and also has a cylindrical shank extending smoothly through a hole in the end of the arm. Each hanger bracket 24 comprises a generally triangularly shaped plate embossed at 39, the embossment being punched centrally to provide an aperture flanged at 40 around its edge. The shank of the stud 23 is swaged at its end to provide two diametrically opposed lugs 42 and the flange 40 is embossed and formed with opposed slots or grooves 41 so that the shank of the stud may be passed through the aperture in the bottom of the embossment 39, the lugs 42 passing freely through the slots or grooves 41. The marginal edge of the flange portion 40 is provided with a cam contour 43 and at high points of the cam the edge of the flange is provided with opposed notches 44 disposed at right angles to the grooves 41. Thus it will be seen that upon rotating the stud 23 or 23' ninety degrees from the position shown in Fig. 4 the lugs 42 will travel up the cams 43 until the lugs drop into the notches 44 thereby interlocking the parts together. Interposed between the end of the arm 27a, or 22, and the embossed portion 39 of the hanger member 24 is a spring anti-rattle washer 45. In assembling the end of either of the arms with the

hanger member 24 the stud 23 or 23', carried by the arm, is inserted through the aperture in the base of the embossed portion 39 with the lugs 42 passing through the grooves or slots 41 in the flanged portion 40 of the embossment. A quick turn of the stud through an angular path of ninety degrees will cause the head of the stud to be drawn tightly against the end of the arm, tensioning the washer 45. The parts will be securely interlocked when the lugs 42 anchor themselves within the notches 44, being yieldingly held therein by the spring 45. The parts may be quickly detached by turning the stud in the opposite direction with sufficient effort to force the lugs out of the notches 44.

Due to the pivotal connection 23, 23' between the hanger members 24 and the lifting arms 22 and 27, the arms are adapted to rotate relative to the hanger members during the raising and lowering operation of the window panel. In the present instance the connection between the hanger members 24 and the window panel 11 is in the form of antifriction rollers which are adapted to reduce the effort required to operate the window panel, especially in connection with the larger windows of automobile bodies. One form of antifriction connection is illustrated by way of example in the drawings. Referring to Fig. 5, each hanger member 24 is generally triangular in shape and at its wider upper end carries a set of three rollers 29 and 29a operable within a guideway formed by a channel member 30 secured, as by spot welding, to the bottom of the glass retainer channel 15. One pair of rollers 29, journaled on the hanger member 24, track along a grooved guideway in the bottom of the channel guide 30, whereas the intermediate roller 29a is journaled at a somewhat higher level and the roller 29a is adapted to track along the upper flanged surface of the channel guide 30. If desired the rollers 29 and 29a may be journaled on the hanger member 24 through the medium of self-oiling bearings thereby increasing the life of the device and reducing friction during operation.

From the foregoing it will be seen that I have provided an improved, simplified and compact window regulator of the cross arm type requiring but a single mounting plate and in which the shorter or balance arm is controlled for swinging movement in a direction opposite to the main arm through the medium of lever mechanism or the like driven from the main arm at a point on the mounting plate adjacent the pivotal axis of the main arm. It will be further noted that control mechanism for swinging the shorter or balance arm comprises a parallel motion mechanism and the construction is such that the arm 27a is adapted to pass by the main arm 22 and also the control link 32 during movement of the window panel between its upper and lower limits of travel. In the illustrated construction the distance between the axis of swinging 20 of the main arm and the point X is the same as the length of the control link 32 between the pivots 31 and 33. Moreover, the distance between the point X and the pivot 28 is the same as the distance between the pivots 29 and 35. Moreover, the length of the control link 32 between the pivots 31 and 33 is the same as the distance between the pivots 28 and 35, and the length of the lever 34 between the pivots 33 and 35 is the same as the angular extension 27b between the pivots 28 and 31. From this construction it will be seen, by comparing the positions of the various

parts in Figs. 2 and 6, that a parallel motion mechanism is provided in which lever 34 and arm extension 27b move in parallelism at all times and control link 32 and main arm 22 also move in parallelism at all times. Thus a very advantageous and easily operated regulator is provided. It will further be noted that the lever 34 whose motion controls the motion of the link 32 and the balance arm 27 is operated from a point 35 offset laterally from the pivotal axis 20 of the main arm 22. This provides a simple operating device in which the proper swinging motion may be imparted to the arm 27 by the motion of the main arm or drive gear 48 adjacent the axis of rotation or turning thereof. The control slot 38 permits movement of the fulcrum 37 vertically during operation of the regulator so as to compensate for the arcuate motion of the pivot 35 during turning motion of the gear 48 as well as the inner end of the main arm 22.

In the operation of the window regulator it will be understood that rotation of the gear 48 in one direction from the pinion on the handle shaft 19 will swing the main arm 22 downwardly, carrying with it the shorter or balance arm 27 due to the pivotal connection 28 between these arms. In lowering the window panel 11 the arms 22 and 27 will swing from the position shown in full lines in Figs. 1 and 2 to the halfway position shown in dotted lines in these figures and to the fully lowered position of the window panel shown in full lines in Fig. 6. In lowering the window panel it will be seen that the pivot 35 moves from a point at the left of an imaginary vertical line passing through fulcrum 37 to a point at the right of this imaginary line, see Fig. 6. In like manner, arm extension 27b and pivot 31 move from a predetermined position at the left of an imaginary vertical line passing through pivot 28 to a similar position at the right of this imaginary line, compare positions of arm extension 27b in Figs. 2 and 6. In raising the window position of Fig. 6 to the full line position of Fig. 2 it will be understood that the reverse action takes place from that above described.

The controlled movement of the angular or elbow extension 27b is of considerable importance in the present embodiment of the invention, this being accomplished through control link 32 and lever 34. As a result it is possible to utilize a cross arm 27 in conjunction with arm 22 to support the window panel at relatively widely spaced points 23 and 23' while at the same time enabling the arm 27 to be swung or rotated about its pivot 28 oppositely to arm 22 from a point on the mounting plate 16 near the pivot 20 while also positively controlling the extent of this pivotal motion of arm 27 so as to maintain the window supporting points 23 and 23' substantially horizontal. Since the path of travel of point 23' approximates more nearly a rectilinear path there is no material tendency of the panel 11 to be shifted laterally to one side or the other by any frictional drag as in the case of certain prior types of window regulators, and in the present embodiment any frictional drag in one direction or the other is materially reduced by virtue of the roller connections 29, 29a between the lifting arms and the window panel. It will further be noted that since the arms 27 and 22 swing in opposite directions the points of support 23 and 23' are increasingly separated as the window panel travels down or up toward

the halfway position, thus achieving a desirable advantage in respect to the stability of the window panel in open positions.

Also it will be seen that since arm 22 and control link 32 extend generally in the same direction, they may be mounted upon a single common mounting plate to one side of the center line of the glass, as shown in Fig. 1, and a remote handle location at 19 may be had. This handle location may be varied, as desired, by variations in the size of the gear 48 and in the lengths of arms 22 and 27. Although these arms swing oppositely, yet the control of arm 27 is such as to avoid too wide a spread of points 23 and 23' as would prevent use of the regulator with a relatively narrow window, such as shown in Fig. 1, having a full drop or range of travel as indicated.

In the event an even more remote handle location than that indicated in Fig. 1 is desired the embodiment of the invention illustrated in Fig. 10 may be utilized. The construction of the regulator in this view is the same as that heretofore described excepting in the following respects. The main arm 46, as in the previous embodiment, is stamped or blanked out in one piece but in this instance is formed with angularly related portions thereby eliminating the necessity of forming the projecting extension 22a. The operation of the regulator is the same, however, since the control link 32 moves in parallelism at all times with the longitudinal axis of the main arm 46 comprising an imaginary line extending through the pivots 20 and 23. In this embodiment also the driving gear is not attached to the inner end of the main arm 46 but more remotely located. Thus the remote handle location is provided by utilizing a longer mounting plate 47 upon which the driving gear 48 is pivoted at 49 spaced laterally from the axis of the rotation 20 of the main arm. Attached to the gear 48 is a third or driving arm 50 which is connected at its outer end to the outer end portion of the balance arm 27 by means of a stud 51 secured to the arm 27 and adapted to travel within a slot 52 in the arm 50. Rotation of the gear 48 from the pinion on the handle shaft 19 will swing the driving arm 50 thereby swinging the balance arm 27 which motion will be imparted to the main arm 46 and the parallel motion members 32 and 34. The movement of the lifting arms in this embodiment will be identical with that in the first described embodiment, the mode of operation being somewhat different in that the driving effort from the gear is applied to the balance arm 27 instead of to the main arm 23 as in the previous embodiment.

In the embodiment of Fig. 10 the distance between pivot 28 and the pivot 35 of lever 34 to the inner end of the main arm is the same as the distance between the pivot 33 of link 32 to the lever 34 and its pivot 31 to angular extension 27b. Moreover, lever 34 between its pivotal connections has the same length as angular extension 27b between its connections and therefore moves in parallelism therewith. Also, link 32 moves in parallelism with main arm 46 when considering the imaginary straight line passing through its pivotal end connections at 20 and 23. The term parallelism as applied to the movement of the various members is understood to refer to imaginary straight lines passing through pivotal connections at opposite ends of the members. Thus, the link 32 moves essentially in parallelism to arm 46 even though the latter is of bent form

for manufacturing reasons. Hence, the parallel motion of the various elements in Fig. 10 corresponds to that of the previously described embodiment.

I claim:

1. A window regulator for raising and lowering a window panel, comprising a swinging driving arm, a balance arm pivoted intermediate its ends to the driving arm at a point intermediate the ends of the latter, said arms when raised extending in diverging relation and swingable in opposite directions past each other during operation and having means for connection at corresponding ends to the lower edge of the window panel, means for swinging the driving arm, said balance arm having an angular extension, a shiftable link connected to said angular extension at a point spaced from the driving arm, and means operatively connecting said link and second named means and cooperating with said extension to maintain said link and driving arm in vertically spaced substantially parallel relation in all operative positions of the regulator.

2. In a window regulator, a fixed support, a swinging main arm pivotally connected at its inner end to the support and adapted to be connected at its outer end to the lower edge of a window panel, a balance arm having a pivotal connection to an intermediate portion of the main arm, said balance arm adapted to be connected at its outer end to the lower edge of the panel at a point spaced from the connection of the main arm with the panel, the inner end of the balance arm extending beyond its pivotal connection to provide an extension, a link pivotally connected to said extension, and means operatively connecting the link to the inner end of the main arm and cooperating with said extension to maintain said link and main arm in vertically spaced substantially parallel relation in all operative positions of the window regulator, the outer end of the balance arm being adapted to pass by the main arm and link during operation.

3. In a window regulator, a main swinging arm pivoted adjacent its inner end to a support, a second swinging arm pivoted on the main arm at a distance from the axis of swinging thereof and having means for connection at its outer end to a window panel, and parallel motion link and lever mechanism for controlling the swinging motion of said arms oppositely to each other with the second arm passing by the main arm during operation, said link and lever mechanism connecting the inner end portions of the arms and lying at the side of the main arm opposite to the window panel in all operative positions of the regulator.

4. In a window regulator, a main swinging arm pivoted adjacent its inner end to a support, a second swinging arm pivoted on the main arm at a distance from the axis of swinging thereof and having means for connection at its outer end to a window panel, and parallel motion mechanism for controlling the swinging motion of said arms oppositely to each other with the second arm passing by the main arm during operation, said mechanism comprising an angular elbow extension of the second arm, a lever fulcrumed on the support at a point spaced from the pivot of the main arm and operatively connected to the inner end of the main arm, and a link connecting said lever and angular extension, said lever and extension being of substantially equal lengths and said link and main arm movable in vertically spaced substantially parallel relation throughout operation of the regulator.

5. In a window regulator, a main swinging arm pivoted adjacent its inner end to a support to swing about an axis and having means at its outer end for connection to a window panel, a second swinging arm pivoted to the main arm outwardly of said axis and having means for connection at its outer end to the window panel, and parallel motion link and lever mechanism connecting inner end portions of the arms for controlling the swinging motion of said arms oppositely to each other with the second arm passing by the main arm during operation, said mechanism lying at the side of the main arm opposite to the window panel in all operative positions of the regulator.

6. In a window regulator, a main swinging arm pivoted adjacent its inner end to a support, a second swinging arm pivoted to the main arm and having means for connection at its outer end to a window panel, said second arm having an extension beyond its pivotal connection with the main arm at the side of the latter opposite to its connection with the window panel, a swinging lever fulcrumed on the support, means for drivingly connecting the lever to an inner end portion of the main arm, link means connecting the lever to said extension for swinging the second arm in response to swinging of the main arm, said lever cooperating with said extension to position the connection between the lever and link means at all times during operation at the side of the main arm opposite to the window panel.

7. In a window regulator, a main swinging arm pivoted adjacent its inner end to a support, a second swinging arm pivoted to the main arm and having means for connection at its outer end to a window panel; said second arm having an extension beyond its pivotal connection with the main arm at the side of the latter opposite to its connection with the window panel, a swinging lever fulcrumed on the support, means for drivingly connecting the lever to an inner end portion of the main arm, link means connecting the lever to said extension for swinging the second arm in response to swinging of the main arm, said lever cooperating with said extension to position said link means and the connection between the lever and link means at all times at the side of the pivotal connection of the main arm to the support opposite to the window panel.

8. In a window regulator, a main swinging arm pivoted adjacent its inner end to a support, a second swinging arm pivoted to the main arm and having means for connection at its outer end to a window panel, said second arm having an elbow extension beyond its pivotal connection with the main arm at the side of the latter opposite to its connection with the window panel, a swinging lever fulcrumed on the support, means for drivingly connecting the lever to an inner end portion of the main arm, link means connecting the lever to said extension for swinging the second arm in response to swinging of the main arm, said lever and extension positioning said link means at all times below the axis of swinging of the main arm and substantially parallel to the latter.

9. In a window regulator, a main swinging arm pivoted adjacent its inner end to a support, a second swinging arm pivoted to the main arm and having means for connection at its outer end to a window panel, said second arm having an extension beyond its pivotal connection with the main arm at the side of the latter opposite to its con-

nection with the window panel, a swinging lever fulcrumed on the support, means for drivingly connecting the lever to an inner end portion of the main arm, link means connecting the lever to the end portion of said extension for swinging the second arm in response to swinging of the main arm, said lever and extension cooperating to position said link means so that the included angle between said lever and link means is less than 180° throughout operation of the regulator from fully raised to fully lowered positions of the window panel.

10. In a window regulator, a swinging arm fulcrumed adjacent its inner end on a support to swing about an axis and having means for connection at its outer end to a window panel, a second swinging arm having means for connection to the window panel, said second arm crossing the main arm and pivoted thereto at a point removed to one side of a line passing through said axis and connection and at the side of said line opposite to the window panel, said second arm having an extension beyond its pivot lying at the side of the main arm opposite to its connection to the window panel, and mechanism connecting said extension and inner end portion of the main arm for controlling the swinging motion of said arms opposite to each other and lying at the side of the main arm opposite to the window panel throughout operation of the regulator from fully raised to fully lowered positions of the panel.

11. In a window regulator, a swinging arm fulcrumed adjacent its inner end on a support to swing about an axis and having means for connection at its outer end to a window panel, a second swinging arm having means for connection at its outer end to the window panel, said second arm crossing the main arm and pivoted thereto at a point offset to one side of a line passing through said axis and connection, said second arm having an elbow extension beyond said pivot extending regularly with respect to the portion of the second arm at the other side of the pivot, and parallel motion mechanism connecting said extension and inner end portion of the main arm for controlling the swinging motion of said arms opposite to each other and lying at the side of the main arm opposite to the window panel throughout operation of the regulator from fully raised to fully lowered positions of the panel.

12. In a window regulator, a main swinging arm, a second swinging arm crossing said main arm at an intermediate portion of the latter and pivoted thereto adjacent the locality of said crossing, said second arm having means adjacent its outer end for connection to a window panel and said arms extending in diverging relation when the panel is at opposite limits of its range of travel, said second arm having a crank extension beyond said pivot extending angularly with respect to the portion of the second arm at the other side of the pivot, a push and pull control link pivoted to said extension at a point spaced from the pivotal connection between the arms, a swinging lever operatively connected at a point spaced from the axis of swinging of said main arm to a part fixed to the inner end of said main arm and pivotally connected to said link for shifting the same and imparting rotational motion to the second arm in a direction opposite to the motion of the main arm, said lever and extension forming with the link and main arm a parallel motion mechanism and said link lying in vertically spaced relation to the main arm at the

side thereof opposite to the window panel in all operative positions of the window regulator.

13. In a window regulator, a main arm adapted to be connected at its outer end to a window panel, a second arm crossing said main arm at an intermediate portion of the latter and pivoted thereto adjacent the locality of said crossing, said second arm being adapted to be connected at its outer end to said panel and having an elbow extension beyond said pivot extending angularly with respect to the adjacent portion of the arm, a control link pivoted to said extension at a point spaced from the pivotal connection between the arms, and means connecting the opposite end of the link and the inner end of the main arm for imparting rotational motion to the second arm oppositely to the motion of the main arm during operation of the regulator, said link being positioned by said means and extension out of parallel overlapping relation to the main arm in all positions of the latter.

14. In a window regulator, a main swinging arm having means for connection adjacent its outer end to a window panel, a second swinging arm crossing said main arm at an intermediate portion of the latter and pivoted thereto adjacent the locality of said crossing, said second arm having means adjacent its outer end for connection to said panel and said arms extending in diverging relation when the panel is at opposite limits of its range of travel, said second arm having a crank extension beyond said pivot extending angularly with respect to the portion of the second arm at the other side of the pivot, a push and pull control link pivoted to said extension at a point spaced from the pivotal connection between the arms, a swinging lever operatively connected at a point spaced from the axis of swinging of said main arm to a part fixed to the inner end of said main arm and pivotally connected to said link for shifting the same and imparting rotational motion to the second arm in a direction opposite to the motion of the main arm.

15. In a window regulator, a support, a main swinging arm pivoted to the support adjacent its inner end, a second swinging arm crossing the main arm and pivoted thereto adjacent the locality of crossing and adapted to be connected at its outer end to a window panel, the inner end of the second arm comprising a crank extension projecting beyond the pivotal connection between the arms, a lever having a fulcrum on the support intermediate its ends spaced from the axis of swinging of the main arm, a push and pull link pivotally connecting one end of the lever and crank extension at points spaced respectively from the said fulcrum and the pivotal connection between the arms, and an operative connection between the opposite end of the lever and the inner end of the main arm for causing the main arm to impart swinging motion to the lever to shift the link and thereby swing the second arm opposite to the main arm.

16. In a window regulator, a support, a main swinging arm pivoted to the support adjacent its inner end, a second swinging arm crossing the main arm and pivoted thereto adjacent the locality of crossing and adapted to be connected at its outer end to a window panel, the inner end of the second arm comprising a crank extension projecting beyond the pivotal connection between the arms, a lever fulcrumed on the support intermediate its ends at a point spaced from the axis of swinging of the main arm, a link connection

13

between one end of the lever and said crank extension, and an operative connection between the inner end of the main arm and the opposite end of the lever at a location spaced from said axis of swinging of the main arm whereby swinging motion of the latter will swing the lever about its fulcrum and impart swinging motion to the second arm oppositely to the main arm.

17. In a window regulator, a main swinging arm pivoted to swing about an axis adjacent its inner end, a second arm adjacent its inner end overlapping the main arm and pivotally connected thereto at the locality of overlapping, the outer end of the second arm adapted to be con-

14

nected to a window panel and the inner end comprising an elbow extension beyond the pivotal connection between the arms, a shiftable link pivotally connected adjacent one end to said extension, and means operatively connecting the opposite end of the link to the inner end of the main arm and actuated thereby to shift the link and swing the second arm oppositely to the main arm, said link being positioned by said means and extension out of parallel overlapping relation to the main arm in all positions of the link and main arm.

JOHN H. ROETHEL.
